UNITED STATES PATENT OFFICE.

WILLIAM S. RICKS AND EVERETT R. DEWBERRY, OF SEARCY, ARKANSAS.

CHURN.

1,364,453.

Specification of Letters Patent.

Patented Jan. 4, 1921.

Application filed September 19, 1919. Serial No. 324,800.

To all whom it may concern:

Be it known that we, WILLIAM S. RICKS and EVERETT R. DEWBERRY, citizens of the United States, residing at Searcy, in the 5 county of White and State of Arkansas, have invented certain new and useful Improvements in Churns; and we do hereby declare the following to be a full, clear, and exact description of the invention, such as 10 will enable others skilled in the art to which it appertains to make and use the same.

This invention relates to an improved churn and the principal object of the invention is to provide a churn which will be 15 simple in construction and comprise a comparatively few parts and which will further be provided with novel means for mounting the receptacle for vertical reciprocating movement, the churn being so constructed that the cover carrying the dasher may be securely but releasably connected with the receptacle and the receptacle with the cover in place, suspended between vertically positioned springs which yieldably 20 suspend the churn and not only suspend the churn but assist in the reciprocating movement thereof.

Another object of the invention is to so construct this churn that the dasher may 30 form a substantially integral element with the cover when connected therewith.

Another object of the invention is to so construct the receptacle that it may be placed in a frame structure rigidly connected therewith and a yoke carried by the cover releasably connected with the bracket or frame structure of the receptacle.

This invention is illustrated in the accompanying drawings, wherein:

40 Figure 1 is a side elevation of the churn in position for use.

Fig. 2 is a vertical sectional view through the receptacle with the cover in place.

Fig. 3 is a transverse sectional view 45 through the receptacle looking toward the cover.

Fig. 4 is a perspective view of the dasher.

Fig. 5 is a perspective view of the supporting frame positioned about the receptacle.

50 The receptacle 10 is cylindrical in shape and provided with a bottom 11 and with an open upper end and may be provided with handles 12 so that the receptacle may 55 be easily lifted. This receptacle is provided

with a supporting frame 13 which is U-shaped and is provided with side arms 14 which extend upwardly along the sides of the receptacle between the handles 12 and are provided at their upper ends with outstanding fingers 15. The arms will be connected with the receptacle by rivets or in any other suitable manner which will provide a rigid connection. A hook or eye-bolt 16 extends through the cross bar of this 60 frame extending beneath the receptacle and also extends through the cross arms 17 which assist in bracing the can or receptacle.

The cover 18 fits upon the receptacle or can 10 and is provided with a depending 70 flange or collar 19 which extends in tight engagement with the inner faces of the receptacle walls so that there will be no danger of leakage. If desired, a suitable gasket may be placed about the collar so that this 75 gasket will be compressed between the cover and the upper edge of the receptacle and thus prevent any danger of leakage. A yoke 20 extends across the cover with its end portions extending beyond the cover and provided with slots which will be positioned above the slots 21 in the outstanding fingers 15 so that securing bolts 22 may be passed through the slots of the fingers 15 and outer end portions of the yoke 20 80 thus securely holding the cover in place when the wing nuts 23 are put in place and tightened. This yoke is held in place by a hook 24 which extends through the yoke and cover and through a reinforcing plate 25 85 positioned against the inner face of the cover. This cover carries the dasher 26, the arms 27 of which extend upwardly and are connected with the collar 19. These arms may be formed integral with the dasher or 90 may be formed of separate strips and riveted or otherwise rigidly connected therewith. In the present form the dasher has been shown provided with two arms which are oppositely disposed but it is to be understood that the number may be varied according to the size of the churn.

When this churn is in use, the cream will be poured into the receptacle 10 and the cover which carries the dasher will then be 105 put in place and secured by the bolts as shown in Figs. 1 and 2. The hooks 16 and 24 will then be connected with the free ends of the springs 28 and 29 carried by the arms 30 and 31 of the supporting brackets 32 and 110

the churn will be assembled as shown in Fig. 1 with the receptacle suspended between the springs. These springs will be of such strength that the receptacle may be freely reciprocated but will be of sufficient strength to prevent the springs from being extended beyond a desired amount when the churn is in use. By giving the receptacle an initial vertical reciprocating movement, it will be caused to vertically reciprocate under the action of the springs and therefore the receptacle does not need to be manually reciprocated during the entire churning process. As the receptacle reciprocates the cream will be thoroughly agitated and very quickly churned into butter. As soon as the churning is completed it is simply necessary to disconnect the receptacle from the springs and remove the cover thus withdrawing with the cover the dasher. The receptacle, cover and dasher can then be very easily and quickly cleaned and put away until further use.

What is claimed is:

A churn comprising a substantially U-shaped frame having its arms disposed uppermost, a receptacle positioned in said frame between the arms, a brace secured to the web portion of the frame and engaging the bottom of the receptacle, a cover for said receptacle, a yoke secured to the cover and having its ends slotted and extended beyond said cover, slotted ears on said arms, fastening means passing through the slots of said ears and the ends of the yoke to secure the cover to the receptacle, and a spring supporting means secured to the bottom of the receptacle and to the cover.

In testimony whereof we affix our signatures in presence of two witnesses.

WILLIAM S. RICKS.
EVERETT R. DEWBERRY.
